UNITED STATES PATENT OFFICE.

CHARLES FREDERICK LEWIS, OF CHICAGO, ILLINOIS.

CALENDAR AND DIARY PAGE.

1,415,883.

Specification of Letters Patent. Patented May 16, 1922.

Application filed September 1, 1921. Serial No. 497,635.

To all whom it may concern:

Be it known that I, CHARLES FREDERICK LEWIS, a citizen of the United States of America, residing at Chicago, in the county 5 of Cook and State of Illinois, have invented certain new and useful Improvements in Calendar and Diary Pages; and I do hereby declare the following to be a full, clear, and exact description of the invention, such as 10 will enable others skilled in the art to which it appertains to make and use the same.

The present invention relates to calendars and diaries but is not, in its application, limited thereto.

15 It is well known that most diaries and calendars are manufactured to cover a single year only, and this is particularly true of the former and of what are generally termed "desk" or "memorandum" calendars. "One- 20 year" calendars and diaries ordinarily are printed in the year preceding that in which they are intended to be used and offered for sale during the latter part of the year in which printed, so that their use will begin 25 with the new year. The need for a calendar or a diary is not necessarily concurrent with the first of January. By purchasing a "one-year" calendar or diary at any time after January 1 of the year for which intended, the 30 buyer secures but a fractional part of a year's service therefrom, and the seller must reduce his price with the decreasing usefulness of the device. If the calendar or diary is not disposed of before the end of the year for 35 which it is printed, it becomes valueless.

The primary object of my invention, therefore, is to provide a calendar or diary which, no matter in what month it is bought, will have a year of usefulness. Secondary to this, 40 my invention affords facilities for ascertaining with certainty the day of the week of the current date, and the day of the week of future or past dates. These, and the provision in a calendar or diary of usefulness 45 extending over more than one year, and such other objects as may hereinafter appear, are attained by the novel construction, arrangement and combination of parts to be hereinafter specifically described and 50 claimed. Reference will now be had to the accompanying drawing forming a part of this specification, wherein the figure is a representation of a diary page or calendar sheet, showing one embodiment of my invention.

55 Throughout the description which fol-

lows and in the drawing referred to above, the several parts of the calendar page or diary sheet are indicated by like reference characters.

The ordinal 1 represents a page of a diary, 60 or sheet of a calendar, of the usual rectangular shape, and whose margins are indicated by 2. Each day of the year is represented by a similar page or sheet. For illustrative purposes, as indicated by the drawing, August 65 5th is the date selected to show the invention, the page or sheet therefor having that date prominently displayed in its upper left-hand corner; as indicated by 3, and, additionally, at the bottom thereof, at 4.

70 Adjacent to the printing of the date at 3, the days of the week upon which that date falls in a number of consecutive years, are shown at 5; the years, indicated by the ordinal 6, to which related being in juxtaposition and in alignment therewith.

75 It is manifest that the printing described above may be arranged upon the sheet or page to permit of any desired binding. A calendar having sheets or a diary having 80 pages such as have been described may be purchased at any time during the first year indicated therein (1921) and have a year or more of usefulness ahead of it. The top line of 5 of each page indicates the day of the 85 week upon which that date falls during 1921. At the beginning of the year 1922, by turning back to the page for January 1, the sheets or pages not used, as of 1921, become 90 available. Each sheet indicates by the second line of 5 the day of the week upon which that date falls in that year. In the figure shown, the calendar or diary pages would, of course, be useful for a whole year, if purchased at any time before January 1, 1925. 95

While a maximum usefulness for five years is indicated in the particular embodiment shown, this period may be increased, or decreased, at the will of the maker. A calendar or diary having a gross usefulness of two or 100 three years however is sufficient for most purposes.

105 It will be apparent that the data supplied by 5 and 6 provide ready reference whereby to determine the day of the week upon which past dates fell or future dates will fall and also that where the page of the calendar or diary is not destroyed by memoranda, that it may be used for several years instead of for a single year.

The pages or sheets are of uniform design each day in the year, except for February 29, where, of course data will be given for the leap years within the limits of the calendar 5 or diary term.

What I claim is new and desire to secure by Letters Patent of the United States, is:—

1. In a calendar or diary having a sheet 10 for each day of the year, indicia showing the date and month and the name of the day of the week upon which said date falls in several successive years.
2. In a calendar or diary, a sheet having 15 indicated thereon a given date of the month and a series of years with the day of the week on which the said date of the month comes in said years relatively indicated adjacent to said years.
- 20 3. In a calendar or diary, a sheet having indicated thereon a given date of the month and a series of years with the day of the week on which the said date of the month comes in said years relatively indicated adjacent to said years, the said date of the 25

month in bolder type than the type of the remainder of the said page.

4. In a calendar or diary, a sheet having indicated thereon a given date of the month and a series of years with the day of the 30 week on which the said date of the month comes in said years relatively indicated adjacent to said years, the said date of the month indicated in juxtaposition to said series.

35 5. A sheet for a diary or desk calendar, having thereon in consecutive order a number of years, and in association with said years, a date of a month, and in conjunction with said years and said date, the name of 40 the day of the week in which the said date falls in each of the said years.

6. In combination in a diary or calendar, a date, a series of consecutive years, and associated indicia whereby to determine the 45 name of the day of the week upon which said date falls in each of said consecutive years.

In testimony whereof I affix my signature.
CHARLES FREDERICK LEWIS.
